UNITED STATES PATENT OFFICE.

MAURICE BALLIN, OF SAN FRANCISCO, CALIFORNIA, ASSIGNOR TO NEUSTADTER BROS.,
OF SAN FRANCISCO, CALIFORNIA, A CORPORATION OF CALIFORNIA.

DESIGN FOR A COLLAR.

50,643.

Specification for Design.

Patented Apr. 24, 1917.

Application filed August 9, 1916. Serial No. 114,061. Term of patent 7 years.

To all whom it may concern:

Be it known that I, MAURICE BALLIN, a citizen of the United States, residing in the city and county of San Francisco and State of California, have invented a new, original, and ornamental Design for Collars, of which the following is a specification, reference being had to the accompanying drawings, forming part thereof.

The figure is a perspective view of the collar illustrating my new design.

I claim:

The ornamental design for a collar, as shown.

MAURICE BALLIN.

Witnesses:

FRANCES V. COLE,
JOHN H. HERRING.
